(57) **CLAIM**

The ornamental design for a hook and loop fastener learning board, as shown and described.

DESCRIPTION

FIG. 1 is a top view of the first embodiment of a hook and loop fastener learning board, showing my new design;
FIG. 2 is a bottom view thereof;
FIG. 3 is a front view thereof;
FIG. 4 is a rear view thereof;
FIG. 5 is a left side view thereof;
FIG. 6 is a right side view thereof;
FIG. 7 is a bottom perspective view thereof;
FIG. 8 is a top perspective view thereof;
FIG. 9 is a top perspective view of the second embodiment of a hook and loop fastener learning board;
FIG. 10 is a top view of thereof;
FIG. 11 is a bottom thereof;
FIG. 12 is a right side view thereof;
FIG. 13 is a left side view thereof;
FIG. 14 is a front view thereof;
FIG. 15 is a rear view thereof; and,
FIG. 16 is a perspective bottom thereof.

1 Claim, 5 Drawing Sheets
